CENTRIFUGAL SWITCH

Kemper M. Hammell, Bloomington, and Robert P. O'Malley, Farmer City, Ill., assignors to Eureka Williams Corporation, Detroit, Mich., a corporation of Michigan

Application June 15, 1946, Serial No. 676,885

1 Claim. (Cl. 200—80)

1

This invention relates to centrifugal switches and has particular reference to a starting switch for single phase induction motors operative for opening the electrical circuit through the starting windings when the speed of the motor is sufficiently high to produce the required torque when operating on the main or running windings.

While many switches of this type have heretofore been devised and used, the construction of such switches has been relatively expensive. This invention contemplates a switch of this type which is simple in construction and design and which is made from a relatively few simple parts. The switch is characterized by its simplicity of design, the relatively low cost of making the same and the dependability of operation thereof.

Principal objects of the invention, therefore, are to provide:

A new and improved centrifugal switch;

A new and improved starting switch for electric motors useful for opening the circuit through the starting windings;

A centrifugal switch which is efficient in operation while simple in construction and hence relatively low in cost to make.

Other and further objects of the invention will be apparent from the following description and claims and will be understood by reference to the accompanying drawings, of which there is one sheet, which, by way of illustration, shows a preferred embodiment and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the appended claim. We also contemplate that of the several different features of our invention, certain ones thereof may be advantageously employed in some applications separate and apart from the remainder of the features.

In the drawings:

Fig. 1 is a fragmentary elevational view of an electric motor embodying the invention;

Fig. 2 is a sectional view taken along the line 2—2 of Fig. 1, looking in the direction of the arrows, and showing in elevation the plate assembly of the centrifugal switch contacts;

Fig. 3 is an enlarged sectional view of the switch with the weights thereof in their extended position;

Fig. 4 is a fragmentary sectional view of the

2

switch taken generally along the line 4—4 of Fig. 3, looking in the direction of the arrows; and

Fig. 5 is a side elevational view of part of the apparatus.

As illustrated in the embodiment of the invention selected for purposes of illustration, the centrifugal switch is designed to function as a starting switch for a single phase induction motor for opening the electrical circuit through the starting windings when the speed of the motor shaft is sufficiently high to obtain the required torque from the motor when running on the running windings.

As shown in Fig. 1, the switch may be arranged about the motor shaft 10 between a bearing 12 therefor and the armature 14. The switch in general comprises a contact assembly indicated generally at 16, a collar 18 which is mounted for slidable movement axially of the shaft 10, a spring 20 for biasing the collar 18 to one position and flyweights 32 operative in response to centrifugal force for shifting the collar 18 axially of the shaft against the force of the spring 20.

25 A U-shaped plate 24 having parallel arms 26 is arranged so that such arms are parallel to the shaft 10 and arranged on the opposite sides thereof, the plate being suitably secured to the armature 14, for example, by means of screws 28. The shaft 10 extends through a central opening in the plate 24 and since the plate is secured to the armature 14, it will rotate with the shaft 10. The ends of the arms 26 are each provided with two tabs or projections 30, such tabs projecting toward each other.

40 Each arm 26 has pivotally associated therewith an angularly shaped flyweight 32. Each of the flyweights 32 may be formed from plate or strip stock and as illustrated includes a central portion or long leg 34, a short leg 36, an arm 38 and a pair of tabs or projections 40. Each weight may be formed by suitable stamping operations from metal stock so that parts thereof are integral. Each weight 32 is arranged to be disposed or nested within the arm 26 of the plate 24. The arms or fingers 38 engage in a seat 42 provided on the periphery of the collar 18. The spring 20 comprises a coil spring which is telescopically arranged relative to the hub of the collar 18 and confined between the collar 18 and the plate 24 so as to bias the collar 18 to the position as illustrated in Fig. 1, when the motor is at rest and during the operation thereof on the starting windings.

45 The tabs of the arms 26 and the weights 32

project in generally opposite directions and are interdigitated relative to each other so as to provide a pivotal mounting for the weights 32 on the arms 26 and so as to prevent lateral shifting of the weights 32 relative to the arms 26. The arrangement is such that the edge 44 of the weights 32 will seat in the corners defined by the tabs 30 and the arms 26 and rock therein during pivotal movement of the weights between their retracted position as shown in Fig. 1 and their extended position as shown in Fig. 3.

The legs 34 and 36 of the weights form a mass which operates in response to centrifugal force during the rotation of the shaft 10 to shift the weights from the position illustrated in Fig. 1 to that illustrated in Fig. 3. As the arms 38 of the weights engage the seats 42 on the collar, the centrifugal force will have to be sufficient before the weights are moved to their extended position to collapse the spring 20. When the speed of the shaft 10 is sufficiently high to obtain the required torque from the running windings of the motor, the centrifugal force of the flyweights 32 will move the same to their extended position, thereby shifting the collar 18 so as to open the electric circuit through the starting windings. Obviously, the speed at which the weights 32 will be moved to their extended position will be dependent upon the mass of the weights 32, the speed of the shaft 10, the force of the spring 20 and the friction in the system. All of this may be readily determined so as to obtain the shifting of the collar 18 to open the switch controlling the starting windings at the desired speed of the motor.

It is likewise evident that when the speed of the motor shaft is reduced below the throw out speed of the weights 32, the spring 20 will be operative to shift the weights to their retracted position as shown in Fig. 1 and to close the switch controlling the starting windings. However, as is well known, the speed at which the weights will be returned to their retracted position will be somewhat less than the speed at which the weights will be moved to their extended position due to the different effective distances which the mass of the weights 32 are in their extended and retracted positions from the center of rotation. Tabs 48 struck out of the plate 24 are arranged to engage the weights 32 so as to form a stop to determine their retracted position while the arms 26 form a stop for determining the extended position of the weights 32.

The contact assembly 16 includes a plate of insulating material 50 suitably secured to the end bell of the motor in the position indicated in Fig. 1. A flexible ring 52 is secured to the plate by means of rivets 54 and includes an arm 56 carrying a switch contact 58 and an embossing or rivet head 60 with which the collar 18 is engageable. A contact 62 is carried by a rigid arm 64 mounted on the plate 50 by means of rivets 65. The contacts 58 and 62 are included in the circuit of the starting windings and when engaged close such circuit.

The arm 66 carried by the plate 50 forms a stop for limiting the movement of the contact 58 away from the contact 62. When the ring 52 is not subjected to the action of the spring 20, the contacts 58 and 62 will be separated as the ring 52 is constructed and arranged so that when relieved of the load of the collar 18 and

the spring 20, it will position the contact 58 away from the contact 62.

The tabs 48 due to their engagement with the flyweights 32 and the engagement between the arms 38 thereof and the collar 18 will limit the axial movement of the collar 18 in response to the spring 20. The electrical circuit for the starting windings is suitably connected to the ring 52 and to the arm 64. The resiliency of the arm 56 and the ring 52 will to a large extent relieve the contacts 58 and 62 of any material load of the spring 20.

While we have illustrated and described a preferred embodiment of our invention, it is understood that this is capable of modification, and we, therefore, do not wish to be limited to the precise details set forth, but desire to avail ourselves of such changes and alterations as fall within the purview of the following claim.

We claim:

A centrifugal switch for an electric motor comprising a U-shaped plate adapted to be mounted on the shaft of said motor with the parallel arms of said plate arranged parallel to and spaced from said shaft and on opposite sides of said shaft, the end of each arm being provided with spaced integral tabs projecting therefrom and toward said shaft, a flyweight for each arm comprising an angular plate member having a central portion disposed between one of said arms and said shaft, said central portion having spaced integral tabs projecting from one end thereof and away from said shaft, said arms being provided with a straight edge between said first named tabs, said tabs on said weight and said central portion defining an angle therebetween slightly greater than 90°, the corner formed by said angle being adapted to engage said straight edge so as to provide a pivotal mounting for said weight upon said edge of said arm, a collar slidably on said shaft, each of said weights having an arm projecting from the pivoted end thereof toward said shaft and engageable with a portion of said collar, a spring associated with said collar and said shaft for moving said collar along said shaft into a first position away from said U-shaped plate and for pivoting said flyweights into a first position with said central portions disposed angularly with respect to said parallel arms, said weights under the influence of centrifugal force pivoting on said pivotal mounting into a second position with said central portions resting against said parallel arms, said latter movement of said weights into said second position moving said collar along said shaft into a second position against the force of said spring, and a pair of switch contacts, one of said contacts being resiliently mounted and arranged to be engaged by said collar upon movement of said collar into one of its positions.
